ATTORNEY.

UNITED STATES PATENT OFFICE.

GEORGE L. SHOOK, OF PORT HENRY, NEW YORK.

BLAST FURNACE.

Application filed August 9, 1922. Serial No. 580,766.

To all whom it may concern:

Be it known that I, GEORGE L. SHOOK, a citizen of the United States of America, residing at Port Henry, in the county of 5 Essex and State of New York, have invented certain new and useful Improvements in Blast Furnaces, of which the following is a specification.

My invention relates to blast furnaces, 10 particularly to the stock line section thereof, and the object of my invention is to provide a long lived lining for the stock line; a lining which will have a wearing surface capable of resisting abrasion due to the impinging of the materials forming the charge, 15 during the charging periods; which will be comparatively inexpensive, and easy to put in place; and which when properly installed will not become loosened either from 20 the shocks due to the entrance of the charge, or by the action of the gases, or distorted to any appreciable degree by the widely varying temperatures to which the upper part of a blast furnace is constantly subjected.

With my object in view, this invention resides not only in the shape and proportions of the lining units, but also in the manner in which the same are installed in the furnace.

My improvements are illustrated in the accompanying drawings, in which:

Fig. 1 is a vertical section through the top of a blast furnace provided with my improved stock line section.

Fig. 2 is a plan view illustrating the relative positions of the lining units when installed.

Fig. 3 is a plan view of one form of my improved lining unit, Fig. 4 is an end elevation of the same, and Fig. 5 is a longitudinal cross section.

Fig. 6 is a plan, and Fig. 7 is a longitudinal section, illustrating one modification of my improved lining unit.

The same reference characters refer to the same parts throughout the several views.

Referring to the drawings, 2 represents the usual metal shell within which is laid the wall of lining brick 3, the upper courses 50 of which embrace and support the hopper 4, the discharge opening thereof being closed by the bell 5, all in the usual manner. A flue (or flues) 6, opens through the wall just below the hopper.

Materials with which the furnace is to be charged are deposited in the hopper 4, and

at the proper time the bell 5 is lowered and the materials, discharging through the opening in the bottom of the hopper, are directed by the inclined surface of the bell 5, against 60 the wall of the furnace as indicated by dotted lines in Fig. 1.

The "stock line" or that portion of the furnace wall against which the materials forming the charge are directed by the bell 65 5, is designed to deflect the charge in a manner which will cause the desired distribution of its component parts, so as to insure a proper mixing of the coarse and fine particles thereof. When the stock line wears 70 so that the shape and diameter thereof is changed, the charge will be improperly distributed and cause irregular furnace conditions the result of which will be misfit 75 iron.

Numerous attempts have been made to protect the surface of the brick lining of furnaces at the stock line, from abrasion due to the impinging of the charge as it enters the furnace, but none of them have been 80 successful in prolonging the life of the lining at the stock line to any great extent. Some of the methods have proven to be actually detrimental rather than beneficial, it being found that when they were used the 85 lining had to be renewed sooner than when only the usual brick lining was employed.

Heretofore the protective element of metal has usually been held in place by being embedded between courses of the usual brick, 90 but in one case with which the applicant is conversant a heavy ring of metal of proper length and diameter was suspended in front of the brick at the stock line by means of bolts embedded in and passing through the brick lining. This failed as it was impractical to attach bolts of sufficient strength to support the shield and withstand the temperatures to which they were exposed.

Heretofore when the protective element 100 was made up of comparatively small units, the units were fastened in place by having a portion thereof embedded between courses of the bricks forming the lining wall; some of the units being L shaped and having 105 one leg embedded between courses of the lining brick, the other leg projecting in front of and shielding adjacent courses of the brick. Other units were I shaped and embedded in a similar manner. When these 110 types are used, it is found that the difference in expansion between the protective unit and

the lining brick, plus the action of the gases on the fire clay which is the general bedding material, soon causes the clay to crumble and the unit to become slightly loosened in its bed. After this takes place, the continued and repeated pounding due to the impact of the charge when it is directed against the unit in entering the furnace, causes the supporting bricks (which are 10 comparatively fragile) to disintegrate and portions thereof to drop out of place, and soon results in the displacement of the unit. After one breach is made the lining soon follows the protective unit and eventually most 15 of the stock line is enlarged and fails to function properly.

After years of experimentation and trial, I have overcome these difficulties and produced a satisfactory and long lived stock line 20 which will last practically as long as the furnace, by means of a lining unit of substantially the shape and relative dimensions, and installed substantially as, illustrated in the accompanying drawings, and hereinafter described.

My improved lining unit is a casting, preferably of white iron and having an overall thickness substantially the same as the thickness of the lining bricks which are 30 to be used. They are wedge shaped and the ends are curved on a radius to conform to the diameter of the furnace in which they are to be used. The width of the segments are to be such that a designated number 35 will complete a circle when placed side by side, with a space of about one quarter of an inch between segments. The length of the segment will of course depend on the size of the furnace and the thickness of the 40 wall which is to be used, I prefer however to have the length about equal to one and one-half the width of the large or wide end of the segment.

Formed in the upper side of the segmental lining unit 7, is a cavity 8, of such shape and size that there is left a comparatively thick wall at the narrow end (which is 45 adapted to be exposed when the unit is set in place in the furnace) and a comparatively thin wall at the bottom, sides, and wide end of said cavity; the comparatively thin walls gradually increasing in thickness before they join onto the thick wall 9, at the narrow end of said unit. Substantial fillets are 50 used in all corners of said cavity so as to lessen the danger of checking as the casting expands and contracts in service. A block 55 27 inches in length would have a wall 5 inches thick at 9, and $\frac{1}{4}$ inch thick at 10.

60 Bolt holes 11, in the sides of the unit, adapted to pass bolts 12, provide means for fastening adjacent units together and preventing their displacement. Instead of using bolts to fasten units in place, I may 65 form projections 14, 15, on top of the side

walls 10, and an opening 16, in the bottom of the unit, so that when successive courses of the units are laid in place (the joints are broken as shown in Fig. 1) the projection 14, on one unit and the projection 15 on the adjoining unit will enter a hole 16, in the bottom of a unit in the succeeding course and so prevent any appreciable lateral displacement of the units after being put in place. As each course of units is laid the cavities in the units are filled with brick bats or other available suitable material.

In placing the segments in position I use a wooden strip as a filler between units, this filler being about one quarter of an inch thick and adapted to hold the units in proper spaced relation from each other. When the furnace is fired these filler strips burn or char and permit the necessary expansion of the units. If there is an unnecessary amount of space in some cases, it soon fills with carbon which prevents any undesirable gas leakage therethrough.

In a blast furnace having my improved lining blocks installed it is desirable to leave 90 a space 17 between the back of the units 7, and the brick lining, and to fill this space with granulated cinder. A space may also be left between the wall 3, and the shell 2, 95 and be filled with the same material.

A blast furnace provided with my improved lining units at the stock line, will not require repairs at that point for a very long period of time; the units themselves are 100 comparatively inexpensive and easily handled, will wear for a very long time, and will not become distorted or get out of place if properly installed; being laid without any 105 bricks interposed and all tied together in the circle, there is nothing which is liable to disintegration and under ordinary conditions of service the completed lining cannot be displaced except by deliberate intention. The units proportioned as shown will last 110 for an exceedingly long period without appreciable wear.

I claim:

1. In a blast furnace, a stock line section faced with courses of metal lining units having a cavity formed in the upper surface thereof, the cavities filled with clayish materials, successive courses in contact with each other, the units in each course slightly separated.

2. In a blast furnace, a stock line section faced with courses of metal lining units having a cavity formed in the upper surface thereof, said cavity filled with clayish materials, successive courses in contact with each other, the units in each course held 120 against more than a limited lateral displacement.

3. In a blast furnace, a stock line section faced with courses of metal lining units having a cavity formed in the upper 130

surface thereof, said courses in substantial contact one with another, the units forming a course slightly separated from each other and held against more than a limited lateral displacement.

4. A lining unit for the stock line of a blast furnace, comprising a metal casting wedge shaped in plan and substantially rectangular in elevation, and having a cavity formed in one side thereof so shaped and proportioned as to leave a comparatively thin wall at the bottom, both sides, and the wide end of said cavity, and a comparatively thick wall at the narrow end thereof.
- 10 5. A lining unit for the stock line of a blast furnace, comprising a metal casting wedge shaped in plan and substantially rectangular in elevation, and having a cavity formed in one side thereof so shaped and proportioned as to leave a comparatively thin wall at the bottom, sides, and wide

end of said cavity and a comparatively thick wall at the narrow end thereof; and means whereby the unit may be connected to adjoining units.

25

6. A lining unit for the stock line of a blast furnace, comprising a metal casting wedge shaped in plan and rectangular in elevation, and having a cavity formed in one side thereof so shaped and proportioned that there is left at the narrow end of said cavity a comparatively thick wall, and comparatively thin walls at the wide end, sides, and bottom thereof, said bottom and side walls gradually increasing in thickness as 30 they approach the point at which they join the said thicker wall at said narrow end; and means whereby said unit may be connected to adjoining units.

30

In testimony whereof I have affixed my 35 signature.

GEORGE L. SHOOK.
